United States Patent Office

Des. 234,141
Patented Jan. 21, 1975

234,141

ELECTRICAL CONNECTOR

Eugene W. McGrane, 887 Colonial Road,
Elizabeth, N.J. 07204

Filed July 24, 1972, Ser. No. 274,277

Term of patent 14 years

Int. Cl. D13—03

U.S. Cl. D26—1 A

FIG. 1

FIG. 2

FIG. 3

FIG. 4

FIG. 5

FIG. 6

FIG. 1 is a perspective view of the electrical connector showing my new design;

FIG. 2 is a side elevational view thereof;

FIG. 3 is a top plan view thereof;

FIG. 4 is a bottom plan view thereof;

FIG. 5 is an end elevational view thereof; and

FIG. 6 is an end elevational view thereof, opposite to that shown in FIG. 5.

I claim:

The ornamental design for electrical connector, as shown.
